UNITED STATES PATENT OFFICE.

GEORGE D. CASE, OF HORSEHEADS, NEW YORK.

SECTIONAL CONCRETE CONDUIT.

1,320,313.

Specification of Letters Patent. Patented Oct. 28, 1919.

Application filed December 18, 1916. Serial No. 137,654.

To all whom it may concern:

Be it known that I, GEORGE D. CASE, a citizen of the United States, residing at Horseheads, in the county of Chemung, and 5 State of New York, have invented certain new and useful Improvements in Sectional Concrete Conduits, of which the following is a specification.

The present invention relates to sectional 10 concrete conduits and has particular reference to new and useful improvements in conduits of this class, whereby the same may be quickly set up for use and the sections thereof firmly connected to form a continuous 15 concrete conduit.

An object of my invention is to provide a sectionalized concrete conduit built up of a plurality of detachable sections, said sections being interconnected to form a continuous 20 conveying body, the various sections thereof being so connected that expansion and contraction of the same is readily accommodated.

My invention further contemplates the 25 provision of a conduit formed in sections which will permit expansion and contraction of the sections under changes in temperature whereby to prevent fracture of the sections.

30 My invention still further contemplates the provision of a sectionalized conduit which may be easily packed for shipment, is simple in construction, cheap to manufacture and may be quickly and easily repaired when occasion requires.

Other objects and advantages to be derived from the use of my improved sectionalized conduit will appear from the following detailed description and the claims, 40 taken with an inspection of the accompanying drawing, in which:

Figure 1 is a side elevational view of a portion of a conduit embodying the improvements of my invention;

45 Fig. 2 is a longitudinal sectional view of the same;

Fig. 3 is a transverse sectional view of the same;

50 Fig. 4 is a side elevation of a modified form of my invention, which also presents the reinforcing means as used with my invention;

Fig. 5 is a transverse sectional view of

a portion of a conduit embodying a modified form of my invention;

55

Fig. 6 is a transverse sectional view of a portion thereof; and

Fig. 7 is a transverse sectional view of another modified form of my invention.

Referring more particularly to the drawings, wherein similar characters of reference designate like and corresponding parts throughout the various views, *a* and *b* designate the half portions of one section of my improved conduit, the section being designated *S* in its entirety.

The portions *a* and *b* are preferably U-shaped in configuration forming a substantially rectangular body when connected. The adjoining marginal edges of the portions *a* and *b* are connected by a tongue and groove as indicated at 1 and 2, the tongue and groove connection of one side of the conduit being relatively opposite that of the other side. This permits universal application of the sections when set up. The portions *a* and *b* may be reinforced by the usual metallic elements indicated by dotted lines and designated 3 and 4.

In connecting adjoining ends of adjacent 80 sections I provide tapered annular extensions 5 and 6 on the portions *a* and *b*, said extensions engaging in complementary annular recesses 7 and 8 formed in the adjoining end of the adjacent section.

In connecting the portions *a* and *b* or the portions of my modified forms and in connecting the adjacent sections a suitable cement may be employed. It will be seen that the manner of connecting the adjoining 90 ends of adjacent sections permit expansion and contraction of the sections under changes in temperature, either radially or longitudinally. The tongue and groove connections between the portions *a* and *b* permits relative longitudinal expansion of the portions as well as radial expansion thereof.

In the modifications shown in Figs. 4, 5 and 6, I provide the lower portion *c* with a projecting tongue 10 on the outer edges thereof to engage in a complementary groove formed in the opposite portion *d* of the section. The said portion *d* is provided with a projecting tongue 11 on the inner edge to engage in a complementary groove formed in 105 the portion *c*.

The portions *c* and *d* are provided with a metal reinforcement extending into the said tongues 10 and 11. The corners 14 of my invention are heavier and thicker thus providing a strong supporting means to receive the thrust of any weight bearing thereon. My reinforcing means comprises a plurality of U-shaped members 16 connected by transverse wire sections 17.

- 10 The connecting and adjoining ends of the adjacent sections are provided with annular extensions and recesses as in the first mentioned form. Where the height of the road is such as not to permit the use of a whole section, I have provided a modified form shown to advantage in Fig. 7. A base slab 15 is provided having a pair of parallel grooves therein adapted to receive the tongues 11. The shoulders on the ends of 20 the U-shaped members are adapted to engage the upper surface of the slab 15 thus permitting the slab to receive the weight bearing on the conduit.

I desire to direct attention to the fact that 25 when the conduit is packed for shipment there are no projecting parts which might possibly become broken rendering a section useless. It will also be apparent that in assembling the sections there are no bolts 30 to be tightened, the only tools necessary for assembling the sections being a trowel for applying the cement. The provision of the

novel tongue and groove connections affords means for rendering the conduit watertight.

35

From the above description taken in connection with the accompanying drawings, it is thought that a clear and comprehensive understanding of the construction, operation and advantages of my invention may be 40 had, and while I have shown and described the device as embodying a specific structure, I desire that it be understood that such changes may be made in said structure as do not depart from the spirit and scope of the 45 invention as claimed.

Having thus fully described my invention, what I claim as new and desire to secure by Letters Patent, is:—

A plastic section for conduit structure, 50 the section being substantially U-shaped in cross section and having tongues extending from its sides and ends for overlapping engagement with the tongues of adjoining sections, and a skeleton reinforcing frame 55 embedded in the section and having longitudinally and transversely extending rods, certain of said rods being embedded in the ribs and extending longitudinally therein to reinforce the ribs throughout the entire 60 lengths thereof.

In testimony whereof, I affix my signature hereto.

GEORGE D. CASE.
